JAMES J. SANTIAGO, OF LOS ANGELES, CALIFORNIA, ASSIGNOR TO JOHN GRANT, OF LOS ANGELES, CALIFORNIA

ROTARY EXPANDING UNDERREAMER

Application filed October 22, 1927. Serial No. 227,966.

This invention relates to rotary expansion reamers for well or bore hole drillings; and a general object of the invention is the provision of a simple compact and strong expansible 5 tool, capable of being expanded and contracted by relative rotation.

There are various characteristic features of the invention, all of which will be best understood from the following detailed description; but I may mention preliminarily that the tool requires only very short relative rotation either to expand or contract, that the cutters or cutter elements are solidly supported in the body against all imposed 15 thrusts, and are supported throughout their lengths; and furthermore that the construction lends itself very readily to a design including relatively long cutting elements which are so shifted, upon expansion, as to 20 present the whole of their length to the wall of the hole. The following detailed description will give an understanding of the invention, by way of a specific illustrative embodiment, reference for this purpose being 25 had to the accompanying drawings, in which:

Fig. 1 is an elevation of a complete tool constructed in accordance with my invention;

Fig. 2 is a central longitudinal section of 30 certain parts of Fig. 1;

Fig. 3 is an enlarged section on line 3—3 of Fig. 2, showing the cutters expanded;

Fig. 4 is a similar cross-section showing the cutters contracted.

In the drawings 10 designates the hollow cylindric body of the tool, this body being provided with longitudinal extending slots 11 which extend in to the interior bore 12 of the body. In this interior bore is located 40 a relatively rotatable mandrel 13 whose upper portion 15, shouldered on the body at 14 for end thrust, is provided with the usual screw-threaded pin 16 for connection with a rotary drill stem. (The structure and purpose of collar 14a and spring 13a will be explained later.) The lower end of the mandrel has a reduced extension 17 which extends through a reduced bore 18 of the body, an end thrust nut 19 being provided on mandrel extension 17 to bear up against a shoul-

der 18a, thus to keep the body from dropping off the mandrel. The lower end of the body is formed for the usual screw-threaded connection at 20 with a drilling bit 21; and the mandrel has a water course 22 leading 55 through it from end to end to carry water down to the water courses of the drilling bit.

That portion of the mandrel which lies opposite the body slots 11 is provided with a plurality of cam faces 25, equal in number 60 to the number of cutter carrying slots 11. The tool may be provided with as few or as many cutters as is desired, or as is practical; it is by a mere matter of choice that I illustrate three cutters here. In each one of 65 the three slots 11 there is mounted a cutter element or cutter carrier 26 which preferably fills the slot completely, being movable radially in and out through the slot but having substantially no looseness either lengthwise 70 or the slot or transversely of it.

Outward movement of each cutter element is limited by laterally projecting wings 26a which extend along the longitudinal edges of the inner face of each element 26, preferably extending from end to end of the element. In the expanded position, as shown in Fig. 3, these lateral wings bear outwardly against the wall of bore 12 at opposite edges of the cutter accommodating slot. The inner 80 face 26b of each cutter element 26 is conformed to fit upon the corresponding cam face 25 throughout both the width and length of face 26b; so that the cutter elements obtain wide-spread bearings upon the cam faces 85 of the mandrel. Furthermore, these faces are, although eccentric to the center of rotation, as circular cylindric faces, so that the cutter elements obtain wide bearing upon the cam faces at any rotational position of the 90 cam. Between the cam faces the cam has radially extending stop ribs 25a, also preferably extending the whole length of the cam. These stop ribs lie in the spaces between the inner ends of adjacent cutters, as is clearly 95 shown in Figs. 3 and 4; and, by coming into contact with the wings 26a, they form rotation stops to limit the rotary movement of the cam in both relative directions.

The cutter elements for this tool may be 100

of any character desired, that is, the cutter elements may carry at their outer edges cutting parts of any suitable character, depending upon the type of work and character of formation for which a particular tool is designed. By a mere matter of selection I have preferred here to show roller cutters 30 mounted rotatively on pins 31, the rollers projecting outwardly beyond the outer edges of cutter elements or carriers 26. I have also preferred to show the total length of each cutting part made up of two such rollers 30. But, however, the ultimate cutting parts are composed, it is to be seen that they may, in their effective cutting length, be substantially as long as the whole cutting element 26. Furthermore, it will be noted that the cutting parts are solidly and directly supported throughout their whole lengths, the cutter elements 26 backing up against the mandrel throughout their whole lengths (or, which is the important feature, on a wide-spread bearing face which includes parts near both ends of the cutter element) and the sliding fit of the cutter elements in the slots gives them lateral support throughout their lengths and also gives them endwise thrust support of the most solid character. Furthermore, it will be noted that the cutter element and cutting parts are shifted out by rectilinear motion, so that one part of the cutting element (for instance, its lower end) is shifted out as much as any other part (for instance, its upper end). Thus the cutter elements and cutting parts may, with proper design of the tool, be made as long as it is desired; those parts of the tool, and also the cam, can be lengthened out to be even proportionately longer than is shown in these drawings.

It will be noted from an inspection of Figs. 3 and 4 that the stop ribs 25a not only perform the general offices of stops to limit rotation of the mandrel and cam, but the parts are so relatively proportioned that when cutter carriers 26 reach their fully expanded positions with their stop wings 26a bearing outwardly against the body wall, the stop ribs 25a come into contact with the cutter elements before the cams have been rotated so far as to wedge the parts too tightly in expanded position.

In the position of Fig. 3, the cutter elements 26 are held against any loose motion, the wings 26a bearing outwardly against the body wall, and the cam faces 25 bearing outwardly against the cutter elements, so that there is no looseness; but at the same time the cams have not wedged the parts so tightly into expanded position as to make it difficult to retract the cam from the position of Fig. 3 to the position of Fig. 4.

Another function performed by stop ribs 25a is that of forming an additional bearing face for the rotative mandrel in the bore of the tubular body. From an inspection of

Figs. 3 and 4 it will be seen that the outer edges of the ribs 25a rotatively bear on the cylindric inner face of the body wall; and in a practical construction of this reamer the outer edge faces of rib 25a will be turned to a true cylindric bearing surface. By this arrangement the mandrel is given a very good radial bearing upon the body throughout the length of the cam. In other words, the mandrel has a good radial bearing within the body, co-extensive with the lengths of the cutter elements and therefore of such a nature and relative positioning as to transmit directly to the body, without any bending stresses on the mandrel, all the radial inward thrusts which may be exerted from the outside on any one or more of the cutters. This is another feature that contributes very largely to the solidity and ruggedness of my design; no bending stresses being exerted upon the mandrel, and all the radial thrusts being taken off the mandrel bearing at its lower smaller end 17.

Another feature of the design shown in the drawings is this; that the exterior surface of the cylindric body is flattened as shown at 10a at each side of each cutter, the flat portions being substantially co-extensive in length with the cutters. By this arrangement, without undue projection of the cutters beyond the cylindric exterior surface of the body, the cutters project further than they otherwise would beyond the immediately surrounding body surface, and thus have better opportunity for obtaining a cutting hold upon the wall of the hole.

The whole result is a very simple, compact, and sturdy tool highly adapted to its intended purposes. It is also very simple in operation. To expand, it is only necessary to rotate the tool in a right handed direction, looking down upon it, after the tool has passed below the lower end of the casing; the drag of the bore wall on the body and on the cutters will cause relative right-hand rotation of the mandrel and its cam, until the position of Fig. 3 is reached; and, thereafter, cutting drag on the cutters will keep the parts in this position. When it is desired to contract the cutters, it is only necessary to pull the tool up to a point where the upper beveled edges 30a of the uppermost cutter parts come into contact with the lower end of the casing, an inward push being thus exerted on the cutters, which push tends to rotate relatively the parts to the position shown in Fig. 4. The cam faces 25 are made rather "steep" for this purpose, and also for the purpose of obtaining a given amount of expansive and contractive movement with a small rotation of the cam. However, if the cam is designed so that inward pressure alone on the cutters will not cause contraction, then a slight rotation in a left-hand direction, either with or without con-

current casing engagement with the cutters, causes contraction.

On the other hand, collapsing action may be assisted, or wholly caused by a means tending at all times to rotate the mandrel and body relatively from the position of Fig. 3 to that of Fig. 4. A coiled spring 13a may be arranged around the mandrel and have one end anchored to the body as at 13b. Its other end may be anchored at 14b to sleeve 14a which is set on the mandrel. In assembling the parts the spring will be slipped into place and its lower end anchored by setting the screw 13b in an eye in its end. Then collar 14a is turned until the screw registers with the eye at the upper end of the spring, and that screw then set in the eye. Then collar 14a is rotated to put the spring under proper tension and the collar set on the mandrel by 20 set screws as shown at 14c. The spring then constantly tends to turn the parts to collapsed position.

I claim:

1. In an expansive reamer, a body, a mandrel therein relatively rotatable on an axis longitudinal of the body, the body being provided with a longitudinally extending slot, an elongated cutter element mounted in said slot to be rectilinearly slideable to and from 25 the central longitudinal axis of the body and mandrel, the mandrel having an eccentric cam face of a length substantially equal to the length of the cutter element, the cutter element having an inner face bearing on said 30 cam face substantially throughout the length of the cutter element, and the mandrel having stop ribs at opposite sides of its cam face, said stop ribs bringing up against the inner end of the cutter element and thus limiting 35 the relative rotation of the mandrel in both directions.

2. In an expansive reamer, a substantially tubular body having a plurality of circumferentially spaced and longitudinally extending slots through its wall, the slots extending 45 through the wall substantially radially to the central longitudinal axis of the body, a plurality of cutter elements mounted one in each said slot, each cutter element occupying its 50 slot substantially fully in both a lateral and a longitudinal direction and movable in its slot only rectilinearly in a direction substantially radial of the body axis, lateral wings along the longitudinal inner edges of the cutter elements, said wings bearing outwardly against the inner wall surface of the body to limit 55 outward movement of the cutter elements, a longitudinal mandrel in the body and relatively rotatable on the longitudinal axis of the 60 body, said mandrel having a plurality of cam faces, one for each cutter element, said cam faces and the inner faces of the several cutter elements contacting over substantially the whole length and breadth of the inner faces 65 of the cutter elements and adapted, upon rel-

ative rotation of the mandrel, to move the cutter elements rectilinearly outwardly, the mandrel also having longitudinally extending stop ribs lying between adjacent cam faces and adapted to limit relative rotation 70 of the mandrel in both directions by bringing up against the inner longitudinal edges of the cutter elements.

3. In an expansive reamer, a substantially tubular body, a mandrel relatively rotatable therein, a cutter movable in the body, the cutter bearing against the mandrel on surfaces that cause cutter movement by virtue of mandrel rotation, and the mandrel having bearing faces on the inner surface of the 75 body wall directly opposite the bearing surface of the cutter against the mandrel.

4. In an expansive reamer, a substantially tubular body, a mandrel relatively rotatable therein, the mandrel having rotative and lateral thrust bearing substantially throughout its length in the tubular body and also having end thrust bearing in the body to prevent 80 relative longitudinal movement of the mandrel, a cam face on the mandrel, a laterally movable cutter element bearing inwardly against the cam face and adapted to be moved outwardly by the cam face on relative rotation of the mandrel and means at 85 the upper end of the mandrel for connecting with a drill stem and thus for putting drilling weight on the mandrel and body.

5. In an expansive reamer, a substantially tubular body with a slot through its wall, a mandrel relatively rotatable in the body and having a lateral thrust bearing on the body 90 wall substantially throughout that portion of its length that is co-extensive with the body slot, and a cutter element in the body slot and bearing inwardly against the mandrel.

6. In an expansive reamer, a substantially tubular body with a slot through its wall, a mandrel relatively rotatable in the body and having a lateral thrust bearing on the body 100 wall substantially throughout that portion of its length that is co-extensive with the body slot, a cam face on the mandrel also substantially co-extensive in length with the body slot, and a cutter element in the body slot and bearing inwardly against the cam face.

7. In an expansive reamer, a body with a longitudinal bore, a mandrel fitting the bore and movable therein, the mandrel having a lateral thrust bearing against the bore wall substantially throughout its length, a sunk cam face in the bearing face of the mandrel, and a laterally movable cutter bearing inwardly against the cam face.

8. In an expansive reamer, a body with a longitudinal bore, a mandrel fitting the bore and rotatable therein, the body wall having a slot therethrough, the mandrel having a lateral thrust bearing against the bore wall 130

substantially throughout that portion of its length that is co-extensive with the body slot, a sunk cam face in the bearing face of the mandrel, and a laterally movable cutter in the body slot bearing inwardly against the cam face.

9. In an expansive reamer, a body with a longitudinal cylindric bore, a mandrel fitting the bore and rotatable therein, the body having a slot through its wall, a cutter movable in and out through the slot, a sunk cam face in the bore fitting face of the mandrel adapted to engage the inner face of the cutter, and the mandrel having rotative and lateral thrust bearing against the wall of the body bore substantially co-extensive in length with the cutter.

10. In an expansive reamer, a body with a longitudinal cylindric bore, a mandrel fitting the bore and rotatable therein, the body having a plurality of circumferentially spaced and longitudinally extending slots through its wall, a cutter fitting each slot to be movable in and out therethrough, the mandrel having a sunk cam face for each cutter, said cam faces being spaced apart by ribs which extend throughout the lengths of the cams and have outer faces bearing against the body bore, to give the mandrel a rotative and lateral-thrust bearing on the bore wall throughout the longitudinal extent of the sunk cam faces.

11. In an expansive reamer, a body with a longitudinal cylindric bore, a mandrel fitting the bore and rotatable therein, the body having a plurality of circumferentially spaced and longitudinally extending slots through its wall, a cutter fitting each slot to be movable in and out therethrough, the mandrel having a sunk cam face for each cutter, said cam faces being spaced apart by ribs which extend throughout the lengths of the cams and having outer faces bearing against the body bore, to give the mandrel a rotative and lateral-thrust bearing on the bore wall throughout the longitudinal extent of the sunk cam faces, said cutters substantially completely filling the body slots and being constrained to move rectilinearly in and out through the slots, and the cam faces being adapted to impart such rectilinear movement by uniform contact with the cutters throughout their lengths.

In witness that I claim the foregoing I have hereunto subscribed my name this 14th day of October, 1927.

JAMES J. SANTIAGO.
